Primary Examiner — Rhea Shields

(74) Attorney, Agent, or Firm — Fay Kaplun & Marcin,
LLP(57) **CLAIM**

The ornamental design for a medical device, as shown and described.

DESCRIPTION

FIG. 1 is a perspective view of a medical device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom thereof.

In the drawings, the broken lines are for the purpose of illustrating a portion of the medical cart and forms no part of the claimed design.
